UNITED STATES PATENT OFFICE

140,920

DESIGN FOR A COMBINATION VANITY AND TABLE

Auburn Taylor, Charleston, W. Va.

Application January 8, 1945, Serial No. 117,331

Term of patent 7 years

(Cl. D33—6)

To all whom it may concern:

Be it known that I, Auburn Taylor, a citizen of the United States, residing at Charleston, in the county of Kanawha and State of West Virginia, have invented a new, original, and ornamental Design for a Combination Vanity and Table, of which the following is a specification, reference being had to the accompanying drawing, forming part thereof.

Fig. 1 is a perspective view of a combination vanity and table embodying my new design.

Fig. 2 is a perspective view of the combination vanity and table of Fig. 1 but showing the appearance of the same with the swingably mounted mirror thereof lowered into horizontal

position so that the back of the mirror may serve as a table top.

Fig. 3 is a front elevation of my combination vanity and table with the parts thereof arranged as in Fig. 2.

Fig. 4 is a perspective view of the combination vanity and table, similar to Fig. 2, but showing the same from the rear rather than from the front.

I claim:

The ornamental design for a combination vanity and table, substantially as shown and described.

AUBURN TAYLOR.
